UNITED STATES PATENT OFFICE.

JOHN H. BEST, OF EDMOND, KANSAS.

WIRE STRETCHER.

Application filed November 1, 1920. Serial No. 421,100.

To all whom it may concern:

Be it known that I, JOHN H. BEST, a citizen of the United States, residing at Edmond, in the county of Norton and State of Kansas, have invented new and useful Improvements in Wire Stretchers, of which the following is a specification.

This invention relates to devices for stretching wire fences and has for its object the provision of an improved device for stretching barbed wire and for holding it stretched so that a splice may be made.

An important object is the provision of a device of this character so constructed as to be fulcrumed upon a post and carrying wire engaging grips which are successively engageable behind successive barbs whereby to exert a step by step pulling action for placing the wire under tension.

An additional object is the provision of a device of this character which will be simple and inexpensive in manufacture, easy to use, highly efficient, durable in service, and a general improvement in the art.

With the above and other objects and advantages in view, the invention consists in the details of construction to be hereinafter more fully described and claimed and illustrated in the accompanying drawings in which—

Figure 1 is a side elevation of the device in use engaged upon a fence post,

Figure 2 is a plan view thereof,

Figure 3 is a plan view showing the device arranged for splicing,

Figure 4 is a side elevation thereof, and

Figure 5 is a perspective view of one of the wire grips.

Referring more particularly to the drawings, the numeral 10 designates a bar which has one end straight and serving as a handle and which has its other end curved, as shown at 11, for fulcruming engagement upon a fence post A. The letter B designates wires to be stretched. The extremity of the curved portion 14 of the bar is provided with a hole 12 and formed at the juncture of the straight portion with the curved portion of the bar is an ear 13 provided with a hole 14. The center of the curved portion is provided with a hole 15.

Associated with the bar 10 are rods 16 and 17, the former of which is provided at one end with an eye 18 pivotally engaged within the hole 12 and the latter of which is formed with an eye 19 pivotally engaged

within the hole 14. The other ends of these rods are formed with eyes 20 and 21, respectively, with which are pivotally connected gripping hooks 22 and 23, respectively, which are identical in construction. Each of these gripping hooks comprises a body 24 apertured at one end for engagement of the pivoting eye therein and having the other end formed with a bill 25. The bill is so arranged with respect to the body as to provide a long narrow space therebetween and this space decreases in size toward the right of the hook.

Engaged within the hole 15 is a link 26 which carries a gripping hook 27 identically the same as the hooks 22 and 23. Connected with the link 26 is one end of a chain 28 which carries at its other end an ordinary hook 29.

In the use of the device the curved portion 11 of the bar is engaged upon the post A and one of the hooks 22 or 23 is engaged upon the wire B to be pulled behind one of the barbs thereon, the particular formation of the gripping member insuring proper holding action upon the wire. The operator then grasps the handle portion of the bar and swings it upon the post so as to pull upon the hook which is engaged upon the wire which will result in a longitudinal pull upon the wire. The other hook 22 or 23 is then engaged with the wire behind a succeeding barb whereupon the bar is swung in the other direction to exert an additional pull, further binding the wire. This operation is continued, alternating the engagement of the grips or hooks 22 and 23 with the wire until the proper tension thereon is obtained, after which it is of course apparent that the wire is nailed onto the post.

If desired, instead of engaging the bar upon the post, the hook 27 may be engaged behind a barb on wire already stretched at the other side of the post and the operation carried on in other respects as before.

When it is desired to make a splice use may be made either of the hook 29 engaged behind a barb or the chain 28 may be engaged about a post with the hook 29 thereon engaged within the link 26 whereupon the device is operated in the same manner as before described to place the wire under tension.

From the foregoing description and a study of the drawings it will be apparent that I have thus provided a very simply con-

2
structed and consequently inexpensive device which is easily operated to tighten fence wires or to hold them under tension while a splice is being made.

5 While I have shown and described the preferred embodiment of my invention, it is of course to be understood that I reserve the right to make such changes in the form, construction, and arrangement of parts as will 10 not depart from the spirit of the invention or the scope of the subjoined claim.

Having thus described my invention, I claim:

In a wire stretcher a hook comprising a

body having one end widened and flattened 15 and formed with a hole for the passage of attaching means, said body having its other end formed with a bill tapered throughout its length and terminating in an outwardly deflected point, the body and bill being rectangular in cross section with opposite angles 20 of the angular body forming the confronting edges of the body and bill, the tapering of the bill defining a wedge shaped opening 25 between the bill and the body.

In testimony whereof I affix my signature.

JOHN H. BEST.
